CLAIM

The ornamental design for an RFID antenna, as shown and
described.

DESCRIPTION

FIG. 1 is a top view of an RFID antenna, showing our
design;

FIG. 2 is a bottom view thereof;

FIG. 3 is an isometric view thereof;

FIG. 4 is an enlarged view of the area labeled “4” in FIG. 1;
and,

FIG. 5 is an enlarged view of the area labeled “5” in FIG. 2.
The broken lines in the drawings define the boundaries of the
enlarged views and form no part of the claimed design.
